UNITED STATES PATENT OFFICE.

EDGAR A. NELSON, JR., OF WASHINGTON, DISTRICT OF COLUMBIA, ASSIGNOR TO HERBERT S. SHEPARD, OF WASHINGTON, DISTRICT OF COLUMBIA.

GAME APPARATUS.

Application filed March 6, 1922. Serial No. 541,496.

To all whom it may concern:

Be it known that I, EDGAR A. NELSON, Jr., residing at Washington, in the District of Columbia, have invented new and useful 5 Improvements in Game Apparatus, of which the following is a specification.

This invention is a game apparatus and has for its object to provide a new and improved game requiring the exercise of 10 skill in the playing thereof as distinguished from mere chance.

The apparatus involves a playing surface provided with electric contacts included in electric circuits which also include signals 15 or annunciations, and manually movable playing elements capable of being manually moved along the surface and designed to be so manipulated as to come to rest upon a pair of contacts so as to close a circuit and 20 actuate the signal or annunciator thereof.

With these and other objects in view, the present invention consists in the combination and arrangement of parts as will be hereinafter more fully described, illustrated in the accompanying drawings and particularly pointed out in the appended claims, it of course being understood that changes in the form, proportion, size and minor details may be made, within the scope 25 of the claims, without departing from the spirit or sacrificing any of the advantages of the invention.

In the drawings:

Figure 1 is a front elevation of a game 35 apparatus embodying the features of the present invention;

Fig. 2 is a top plan view of Fig. 1;

Fig. 3 is an enlarged detail vertical sectional view taken longitudinally through the 40 rear end of the game table and showing the manner of securing electric conductors upon the table;

Fig. 4 is a view similar to Fig. 3, but in a different vertical plane, and showing a 45 metal ball resting upon and electrically connecting adjacent conductors of an annunciator system;

Fig. 5 is a detail fragmentary plan view 50 illustrating the trough or gutter across the rear end of the gametable;

Fig. 6 is a diagrammatic view illustrating the annunciator circuits;

Figure 7 is a detail perspective view showing one of the game balls and a holder for the temporary support thereof; 55

Fig. 8 is a diagrammatic view of a modified annunciator system;

Fig. 9 is an enlarged detail of a part of Fig. 8.

Fig. 10 is an enlarged detail fragmentary 60 view showing the means for locking the back-stop.

The present game is played upon a flat, level surface, and in the embodiment of the game shown in the accompanying drawings, the playing surface is a table top 1, of any suitable construction, supported upon leg standards 2 in any desired manner. 65

Extending along the longitudinal side edges of the table are upstanding guard 70 walls or flanges 3, rising a suitable distance above the table top or playing surface. The playing surface is divided into a plurality of divisions or alleys by means of longitudinal partition strips 4, each alley being open 75 at its front end and open or closed at its rear end as may be desired.

Extending transversely across the top of the playing surface at the rear end thereof are bare and exposed electric contact members 5, grouped in pairs designated A, B, C and D, which lie flat upon the top of the playing surface and are connected in electric circuits as best illustrated in Figure 6. The successive pairs of contacts are 85 spaced a suitable distance by means of spacers 6 of suitable insulating material. As best illustrated in Figure 4, it will be seen that each insulator strip 6 projects above the contact members for a purpose as 90 will be hereinafter explained.

The electric system includes a source of electricity as, for instance, a battery 7, from which a conductor 8 leads to a plurality of signals or annunciations designated 9, 10, 11 95 and 12, respectively, which may be of any character, as, for instance, electric lamps. Each lamp is connected in series with the battery through corresponding contact members 5, the conductors being designated 13, 14, 15 and 16, each of which is connected to one end of a contact member 5 of one of the pairs of contact members. The other contact member of each pair of contact mem-

bers is connected to a common return conductor 17 by means of suitable conductors 18, 19, 20 and 21. The return 17, of course, is connected with the battery 7, and preferably includes a switch 22, which, when closed, places the electric system in condition for operation. It will, of course, be understood that when the switch 22 is closed, the various annunciator circuits are open, because the contact members 5 of each pair, A, B, C and D, are unconnected. Each circuit may be closed by bridging the contacts thereof by a suitable conductor, as, for instance, a metallic ball, which has been designated 23, one of such balls being shown in operative position in Figures 2, 4 and 6 of the drawings, wherein it will be seen that the ball is resting upon the bare members of a pair of contacts 5, from which it will be understood that the ball operates as a temporary switch member for connecting the contacts 5 and closing the circuit containing said contacts. The lamps or other devices 9, 10, 11 and 12, will be energized or operated in accordance with the closing of the circuits in which they are included. Any one of the circuits will be closed by a ball or other electrically conductive playing member which rests in contact with and bridges the contact members of a pair of contacts.

By reference to Figure 6 of the drawings, it will be seen that one contact member of each pair of contacts is connected at one end with one side of the battery 7, while the other contact member is connected at its other end through one of the lamps and the lead 8 to the opposite side of the battery.

It will here be explained that the insulating strips 6 serve not only to insulate successive contact members, but also operate as retarders to retard the motion of a ball rolling across the contacts. The insulator strips also serve to center a ball upon a pair of contact members so as to insure a proper seating of the ball and to obtain an effective contact between the ball and the contact members.

As hereinbefore indicated, the rear ends of the respective alleys may be open, as clearly indicated in Figures 3, 4 and 5 of the drawings, and a suitable trough or gutter 24 is provided across the rear end of the table and disposed so as to receive such balls as roll entirely across the series of contacts, and said trough or gutter is inclined downwardly from one end, and has its lower end connected, by means of a bend or elbow 25 with a longitudinal gutter 26, extending alongside of the table to the front end thereof, and inclined downwardly sufficient to insure the travel of the ball to the front end of the gutter, which front end is closed, as indicated at 27, so as to prevent escape of the balls from the gutter at the front end of the

table. By this arrangement of troughs or gutters, it will be seen that such balls as pass beyond the rear end of the table are received in the gutter and automatically returned to the front of the table in position 70 for repeated use.

By reference to Figure 5 of the drawings, it will be seen that the gutter 24 is provided at its lower end and adjacent the bend or elbow 25 with a deflector 28, which reduces 75 the transverse dimension of the gutter adjacent its lower discharge end, and compels the ball to strike a concave deflector 30 at the opposite side of the gutter, and constituting one wall of the elbow 25, whereby 80 the balls are directed in a satisfactory manner around the elbow and are prevented from rebounding into the gutter 25, as would occur in the absence of the concave deflector 29.

In the embodiment of the apparatus as shown in Figures 1 and 2, it will be explained that the battery is contained within a suitable casing or battery box 31, hung beneath the bottom of the table, while the 90 lamps are supported at a suitable elevation above the rear end of the table in a frame including uprights 32 rising from opposite sides of the table.

The present arrangement of lamps lends 95 itself admirably to advertising purposes, in that advertising space may be provided around the respective lights, as indicated at 33, 34, 35 and 36. If desired, an advertising panel 37 may be provided upon the 100 tops of the uprights 32 above the panels 33 to 36, inclusive. Each lamp is, of course, given a suitable designation, so as to distinguish the several lamps. In the present embodiment, the lamps have been designated 105 by the numerals "1", "2", "3", and "4", respectively, displayed in the advertising panels and located adjacent the lamps. There is one lamp for each alley, and each lamp is in vertical alinement with its corresponding alley, the alleys and the lamps being given corresponding designations, in that the alleys are numbered "1", "2", "3" and "4", as best indicated in Figure 2 of the drawings.

While Figures 1 and 2 of the drawings show a lamp for each alley, it will here be explained that the number of lamps is not governed by the number of alleys but, as will be readily understood from an examination of Figure 6, the number of lamps is governed by the number of pairs of contacts. In other words there is a lamp for each pair of contacts, and any number of pairs of contacts may be employed. In each of Figures 1 and 2, the lamps are shown above and in alignment with the respective alleys, but it is quite apparent that the positions of the lamps are not governed by the alleys, as the lamps may be given any location, and may 130

also be given any arbitrary numbering or other designation without reference to the designations of the alleys.

Each playing ball 23 is temporarily supported at the front of the table in a block or holder 38, which rests upon the top of the table and in one of the alleys, and is provided with a depression or concavity 39 to form a seat or socket for retaining the ball. Each ball holder or retainer is provided with a number or designation, as shown in Figures 2 and 7, there being one block or holder for each alley.

It will of course be understood that the manner of using the game apparatus, as just described, is only one way of using it. By increasing the pairs of contacts and the lamps controlled thereby, a wide range of play may be obtained, and the game may be played and scored in the manner of playing and scoring the well known bowling game.

In using the game apparatus, the players stand in front of the table and opposite the open front ends of the respective alleys. Each player rolls a ball in his respective alley with the object of having the ball come to rest on the members of a pair of contacts 5, and thereby energize one of the lamps. The contacts which are in the circuit for the lamp bearing the highest number, are preferably located at the front of the series of contacts, for the reason that this is the most difficult location in which to have the ball eventually come to rest. Some of the balls will, of course, travel across the series of contacts and drop into the trough 24 at the rear end of the table and be returned to the front end of the table through the longitudinal trough 26. Such balls as remain on the table and on contacts, will, of course, close certain circuits and energize the lamps thereof. The player whose ball closes the circuit including the lamp of the highest number, of the lamps which are energized, is the winner. The balls which remain on the contacts, after the winner has been announced, may be brushed off into the trough or gutter 24 and permitted to return to the front of the table where it will be replaced upon the respective ball holders or retainers. While I contemplate numbering each ball to correspond with the number on its ball holder or retainer and the alley in which it is to be rolled, this is not essential, as any ball may be returned to any ball holder or retainer. The winner may be accurately determined by noting the number of the alley in which is the ball which has closed the circuit of the highest number shown, the person having the ball holder or retainer bearing the number of the alley in which said ball is located being the winner. No confusion, therefore, can arise as to which of the players rolled the

ball which closed the circuit of the lamp showing the highest number.

A foul line 40 is provided transversely across the playing surface at a suitable distance from the front end of the table. Such balls as pass beyond the foul line are in play and cannot be rolled again even though the balls do not reach the series of contacts. Such balls as do not reach the foul line may be again rolled. Should a tie result, by reason of two or more balls being included in the one circuit showing the highest number, the players who rolled such balls are permitted to roll again.

While not absolutely essential to the operation of the game, a guard 41 may be provided across the front of the table at a suitable distance therefrom, such that players standing in front of the guard, will be able to reach the front portion only of the table so as to pick up the ball retainers and balls, and will be compelled to deliver the ball on the front end of the table and will be prevented from reaching over and delivering the ball at any material distance in rear of the front end of the table. If desired, the guard may have side members 42 overlapping and extending in substantial parallelism with opposite sides of the table. One or more persons having charge of the game table may stand in the space between the table and the guard without interference by the players and without interfering with the free movement of the players.

While the electric contacts may be secured to the table in any desired manner, a satisfactory construction and arrangement has been shown in Figure 3, which is a sectional view taken through one of the divisional strips 4, which strips are secured to the table top 1, at the rear end thereof, by means of suitable screws 43 and 44. The conductors 5 and the insulating strips 6 pass beneath the strip 4, and a spacing member 45, preferably of some relatively hard insulating material, is placed between the members of each pair of contacts. When the strip 4 is drawn down by the screws 43 and 44, the contacts 5, the spacers 45 and the insulator strips 6, will be crowded down and clamped snugly in place so as to hold the several parts rigidly in their proper spaced relation without the employment of individual fastenings, such as double pronged fastening devices which are liable to work loose. To prevent the contacts and associated parts from spreading, under the clamping action of the strip 4, a suitable abutment 46 is provided across the rear end of the table, which may be in the form of a separate strip, as shown, or might be integral with the strip 4 or with the table 1. Another abutment is provided at the front end of the series of contacts, and in the present embodiment, this front abutment is

formed by the rear end of a thick piece of linoleum 47, which covers the entire top of the table and constitutes the playing surface, said linoleum being held in place by 5 the strips 4, which are secured to the table top by means of screws 43 and 44, and by means of other fastenings designated 48 as indicated in Figure 2 of the drawings.

In Figures 8 and 9 I have shown a modification to permit the operation of the game in the manner of a shuffle board, the movable playing element, designated 43, being flat or in the form of a disc rather than of a ball. In this arrangement, instead of employing spaced contact members, I employ 10 a flat strip 44 of non-conducting material which is provided upon its under side with a plurality of bowed leaf springs 45 having their middle portions resting upon the table 15 top or playing surface so as to support the strip 44 in an elevated position. The adjacent springs 45 are connected by conductors 46, and one of the terminal springs is connected by a conductor 47 and the lead 17 20 connected to one side of the battery 7 in the manner shown and described in Figure 6. The conductor 8 which leads from the other side of the battery 7 includes lamps or 25 annunciators 9 and 10 as hereinbefore described, while the conductors 13 and 14 lead from the respective lamps and extend alongside of the respective strips 44. A conduct- 30 ing member 47 extends from each conductor 13 and 14 beneath the strip 44 and above 35 and out of contact with the adjacent spring 45, it of course being understood that there is a contact 47 for each spring 45. When 40 the playing member 43 is slid along the playing surface and comes to rest upon one 45 of the strips 44, the weight of the playing member will depress the strip until one of the contacts 47 engages the adjacent spring contact 45, thereby completing a circuit and energizing the lamp or annunciator included 50 in said circuit. Between adjacent contact strips 44 there is an insulator strip 48 which is also supported by bowed leaf springs, indicated in dotted lines and designated 49, in order that the insulator strip may be de- 55 pressed under the weight of the playing member when the playing member rests partly on the insulator strip and partly on the contact strip. It will of course be understood that the distance between adjacent 60 contact strips is greater than the width of the playing member in order that two contact strips may not be depressed by a single playing member or element.

It will here be explained that in the ball 65 form of the apparatus, the ball must be a conductor of electricity so as to constitute a switch member for connecting the members of a pair of contacts, whereas in the other form of the apparatus the movable playing element need not be a conductor

of electricity, as it functions merely as a weight to depress the contact strips.

Each insulator strip 6 is rounded or provided with opposite inclines so as to prevent a ball from coming to rest on the insulator 70 strip, thereby insuring a proper seating of the ball on the pair of contacts.

In order to prevent rusting of the surface of the metal ball and to improve the contact surface thereof, I provide the ball 75 with a suitable surface coating, as for instance nickel.

Instead of having the playing surface entirely unobstructed at its rear end, as shown in Fig. 3, a wall or back-stop 50 may be 80 provided, as shown in Fig. 4, such wall extending entirely across the width of the playing surface and cutting the latter off from the rear transverse trough, whereby all balls that are rolled will remain on the 85 playing surface. While this wall or back-stop may be fixed, it is preferred to movably mount the same so that it may be moved out of the path of the balls in order that they may escape into the trough. Any mov- 90 able mounting of the wall may be employed, as for instance by supporting the same upon hinges, one such hinge being shown at 51. As indicated in Fig. 10, the wall may be 95 held or locked in its upright operative position, as for instance by means of a bolt 52.

What is claimed is:

1. A game apparatus comprising a playing surface, a plurality of electric circuits including individually distinguished signals or annunciators, a series of bare and exposed contacts extending transversely across the playing surface and divided into pairs, each pair of contacts being included in one of the electric circuits, and a movable playing member of conductive material, said playing member capable of being manually moved upon the playing surface and of a size to bridge a pair of contacts and close the circuit thereof. 100

2. A game apparatus comprising a playing surface, a movable playing member of electric conductivity and capable of being manually moved along the playing surface from the front to the back thereof, a plurality of electric circuits including individually distinguished signals or annunciators, and a series of bare and exposed parallel contacts extending transversely across the playing surface adjacent the rear portion thereof and in the path of movement of the playing member, said contacts being divided into pairs, each pair of contacts being included in one of the circuits, and the playing member being of a size to bridge a pair of contacts and thereby close the circuit thereof. 115

3. A game apparatus comprising a playing surface, pairs of bare and exposed parallel contact members extending trans- 120

- versely across the playing surface, a source of electricity, a lead extending from each side of the source of electricity, one of the contacts of each pair being connected to the 5 lead extending from one side of the source of electricity, the opposite end of the other contact of said pair of contacts being connected with the lead extending from the other side of the source of electricity, a signal 10 or annunciator included in each circuit and distinguished from each of the other signals, and a manually movable playing member of electric conductivity capable of being moved along the playing surface and across the contacts, said playing member being of a size to bridge a pair of contacts and close the circuit thereof.
4. A game apparatus comprising a playing surface, pairs of bare and exposed parallel contact members extending transversely across the playing surface, a source of electricity, a lead extending from each side of the source of electricity, one of the contacts of each pair being connected to the 15 lead extending from one side of the source of electricity, the opposite end of the other contact of said pair of contacts being connected with the lead extending from the other side of the source of electricity, a signal or annunciator included in each circuit and distinguished from each of the other signals, and a manually movable playing member of electric conductivity capable of being moved along the playing surface and across the contacts, said playing member being of a size to bridge a pair of contacts and close the circuit thereof.
- 20 5. A game apparatus comprising a playing surface, pairs of substantially parallel contact members extending transversely across the playing surface, a source of electricity, a lead extending from each side of the source of electricity, one of the contacts of each pair being connected to the lead extending from one side of the source of electricity, the opposite end of the other contact of said pair of contacts being connected with the lead extending from the other side of the source of electricity, a signal or annunciator included in each circuit and distinguished from each of the other signals, insulator strips between adjacent contact members of successive pairs, said insulator strips projecting above the top 25 surface of the contact members, and a manually movable playing member of electric conductivity capable of being moved along the playing surface and across the series of contacts, said playing member being of a size to bridge a pair of contacts and close the circuit thereof, the several insulator strips also constituting frictional retarders in the path of movement of the playing member.
- 30 6. A game apparatus comprising a playing surface, pairs of substantially parallel contact members extending transversely across the playing surface, each pair of contacts being included in an electric circuit which also includes a signal or annunciator, insulator strips separating successive pairs of contacts and extending above the top 35 surface of the contacts, and a movable playing member in the form of a metallic ball capable of being rolled along the playing surface and across the contacts, the members of each pair of contacts being spaced for engagement with opposite sides of the ball when it comes to rest upon any pair of contacts, the insulator strips constituting frictional retarders in the path of the ball and also serving to center the ball on the contacts.
- 40 7. A game apparatus comprising a playing surface, a pair of bare and exposed substantially parallel contact members extending transversely across the playing surface, an electric circuit including the contact members and also including a signal or annunciator, a manually movable playing member in the form of a metallic ball capable of being rolled along the playing surface and across the contacts and of a size to bridge the contacts and close the circuit when the ball comes to rest between the contacts, a downwardly inclined trough extending transversely across the playing surface and in rear of the contact members, and a forwardly extending downwardly inclined trough leading from the lower end of the transverse trough to the front of the playing surface, the playing surface in rear of the contact members being unobstructed to permit the movable playing member to escape from the rear end of the playing surface and drop into the transverse trough and be carried to the front of the playing surface in the longitudinal trough.
- 45 8. A game apparatus comprising a playing surface, a plurality of electric circuits including signals or annunciators, a series of bare and exposed parallel contacts extending transversely across the playing surface and divided into pairs, each pair of contacts being included in one of the electric circuits, and a movable playing member capable of being manually moved upon the playing surface into cooperative relation with the pairs of contacts for selectively closing the circuits.
- 50 9. A game apparatus comprising a playing surface, a movable playing member capable of being manually moved along the playing surface from the front to the back thereof, a plurality of electric circuits including individually distinguished signals or annunciators, and a series of bare and exposed parallel contacts extending transversely across the playing surface adjacent the rear portion thereof and in the path of movement of the playing member, said contacts being divided into pairs, each pair of contacts being included in one of the circuits, and the playing member being capable of cooperation with respective pairs of contacts for selectively closing these circuits.
- 55 10. A game apparatus comprising a playing surface, a plurality of electric circuits including signals or annunciators, advertising panels associated with the signals or annunciators, pairs of contacts for the respective electric circuits, and a movable playing member capable of being manually moved upon the playing surface selectively into cooperation with the pairs of contacts.
- 60 11. A game apparatus comprising a playing surface, upright advertising panels dis-

- posed above the playing surface and facing the front thereof, a plurality of electric circuits including signals or annunciators in cooperative relation with the advertising 5 panels, pairs of bare and exposed contacts for the respective circuits and disposed transversely upon the playing surface, and a movable playing member capable of being manually moved upon the playing 10 surface selectively into cooperative relation with the pairs of contacts.
11. A game apparatus comprising a playing surface, a series of bare and exposed substantially parallel contacts extending 15 transversely across the playing surface and divided into pairs, an electric circuit for each pair of contacts, a frame rising above the playing surface, a plurality of advertising panels carried by said frame, signals 20 or annunciators included in the circuits and supported on the frame in cooperative relation with the respective advertising panels, and a movable playing member capable of being manually moved upon the playing 25 surface selectively into cooperative relation with the contacts.
12. A game apparatus comprising a playing surface, a plurality of electric circuits including individually distinguished signals 30 or annunciators, a storage battery included in the electric circuits, a series of bare and exposed parallel contacts extending transversely across the playing surface and divided into pairs, each pair of contacts being included in one of the electric circuits, 35 and a movable playing member capable of being manually moved upon the playing surface selectively into cooperative relation with the contacts.
- 40 13. A game apparatus comprising a playing surface, a plurality of electric circuits including signals or annunciators distinguished one from the other, exposed and bare contacts included in the circuits and located on the playing surface and arranged in pairs, and a movable playing member of conductive material, said playing member capable of being manually moved upon the playing surface and of a size to bridge any pair of contacts and close the circuit thereof.
- 45 14. A game apparatus comprising a playing surface, a series of bare and exposed contact rods extending transversely across the rear portion of the playing surface and divided into successive pairs, electric circuits, one circuit for each pair of contacts, a frame rising above the playing surface and provided with a plurality of panels adapted 50 to contain advertising matter, an electric lamp at each panel and adapted to illuminate the panel, each electric light being included in one of the electric circuits, and a metallic ball capable of being rolled along 55 the playing surface and across the contact rods, the members of each pair of contacts being spaced for engagement with opposite sides of the ball when it comes to rest upon any pair of contacts.
- 60 15. A game apparatus comprising a playing surface divided into a plurality of longitudinal parallel alleys, a plurality of electric circuits including signals or annunciators distinguished one from the other, a series of exposed and bare contact rods extending transversely across the playing surface of the several alleys and included in the electric circuits and arranged in pairs, and a movable playing member of conductive material, said playing member capable of being manually moved upon the playing surface of any of the alleys and of a size to bridge any pair of contacts and close the circuit thereof. 70
- 65 16. A game apparatus comprising a substantially horizontal playing surface, parallel longitudinal partition strips provided upon the playing surface and dividing the same into a plurality of alleys, a series of bare and exposed contact rods extending across the playing surface of the several alleys and divided into pairs, electric circuits including the pairs of contact rods, individually distinguished signals or annunciators included in the electric circuits, 80 and a movable playing member of conductive material capable of being manually moved upon the playing surface of any of the alleys and of a size to bridge any pair of contacts and close the circuit thereof. 85
- 70 17. In a game apparatus, a base, a series of exposed and bare contact rods extending across the base, a plurality of parallel longitudinal strips on the base and dividing the surface thereof into a plurality of alleys, said strips extending transversely across the contact rods, and fastening devices securing the strips to the base and drawing said strips snugly against the contact rods to hold them in place. 90
- 75 18. In a game apparatus, a base, a series of exposed and bare contact rods extending across the base, a plurality of parallel longitudinal strips on the base and dividing the surface thereof into a plurality of alleys, said strips extending transversely across the contact rods, fastening devices securing the strips to the base and drawing said strips snugly against the contact rods to hold them in place, and spacing devices interposed between adjacent contact rods and lying between the base and the strips and gripped therebetween. 105
- 80 19. In a game apparatus of the character described, a base, a series of bare and exposed parallel contact rods extending transversely across the base and divided into pairs, insulation strips interposed between successive pairs of contact rods and extending above the latter, longitudinal 110

partition strips extending along the base and across the contact bars and insulation strips, and means securing the partition strips to the base and drawing the partition strips down upon the insulation strips and the contact rods to secure the same in place.

20. In a game apparatus of the character described, a base, a covering of linoleum upon the base and constituting a playing surface, said linoleum terminating short of the rear end of the base, bare and exposed contact rods lying upon the base and in rear of the linoleum and extending transversely across the base, longitudinal partition strips extending along the linoleum and across the contact rods, and means securing the partition strips to

the base and clamping the linoleum and the contact rods between the base and the strips.

21. In a game apparatus of the character described, a base, a sheet of surfacing material upon the base and constituting a playing surface, said surfacing material terminating short of the rear end of the base, bare and exposed contact rods lying upon the base and in rear of the surfacing material and extending transversely across the base, longitudinal partition strips extending along the surfacing material and across the contact rods, and means securing the partition strips to the base and clamping the surfacing material and the contact rods between the base and the strips.

EDGAR A. NELSON, JR.
